PEDAL

James Back, Dayton, Ohio

Application April 30, 1956, Serial No. 41,261

Term of patent 14 years

(Cl. D90—14)

Fig. 1 is a view in perspective of a pedal, showing my new design the bottom of the pedal being substantially the same as the top thereof;

Fig. 2 is a fragmentary view in front elevation thereof, the rear being substantially the same;

Fig. 3 is an end view of Fig. 1; and

Fig. 4 is a view like Fig. 3, showing the opposite end. I claim:

The ornamental design for a pedal, as shown and described.
